(57) **CLAIM**

The ornamental design for a foot pedal with weight measuring sensors for vehicles, as shown and described.

DESCRIPTION

1. Foot pedal with weight measuring sensors for vehicles
1.1 is a front perspective view of a foot pedal with weight measuring sensors for vehicles embodying our new design;

1.2 is a front elevation view thereof;

1.3 is a rear elevation view thereof;

1.4 is a right side elevation view thereof;

1.5 is a left side elevation view thereof;

1.6 is a top plan view thereof; and

1.7 is a bottom plan view thereof.

The broken lines in the drawings illustrate portions of the foot pedal with weight measuring sensors for vehicles that form no part of the claimed design.
